Inventor,

William Barnak,

By Frank S. Appelman,

Attorney

UNITED STATES PATENT OFFICE

WILLIAM BARNAK, OF NANTICOKE, PENNSYLVANIA

FIREARM

Application filed March 19, 1931. Serial No. 523,915.

This invention relates to firearms and to the application of so-called "sling straps" to the stock of the firearm, the said invention relating particularly to an automatically controlled means for housing the said strap and automatically adjusting the said strap as to length, thereby adapting it for use by persons of different statures and those having different arm lengths.

10 It is well known that in firearms where accuracy of aim is desired, the slings or bracing straps employed are in ordinary practice detachably applied to the firearms so that there is liability of loss of the strap when it is removed.

15 Through the employment of this invention, the strap is held and practically concealed when not in use in a storage chamber formed in a part of the firearm structure and preferably in the butt of the stock.

20 It is an object furthermore to provide means whereby the strap may be wound on itself in the said chamber, the said invention also including means for holding the strap 25 at predetermined adjustments after a length of the strap has been drawn from the chamber, the said retaining means being easily manipulated for securing the strap or releasing it.

30 A further object of the invention is to provide an adjusting device at the outer end of the strap, whereby it may be lengthened or shortened in a novel way and securely held in the different positions of adjustment; and 35 the invention furthermore includes a means for anchoring the adjusting means to a part of the firearm structure so that it will not accidentally disengage and can only be disengaged by manipulation which correctly locates one part with relation to the other part.

40 The broad idea of the invention is susceptible of different physical embodiments, some of which are illustrated in the accompanying drawings forming part of this application, the said drawings serving as illustration of means by which the invention can be carried into practice without departing from the spirit of the invention or the scope thereof as embraced in the accompanying claims.

50 In the drawings,—

Figure 1 illustrates a view in side elevation of a firearm with a device embodying the invention applied thereto;

Figure 2 illustrates a sectional view on the line 2—2 of Fig. 1;

Figure 3 illustrates a sectional view on the line 3—3 of Fig. 2;

Figure 4 illustrates an enlarged detail view of a connection at the outer end of the sling strap and the firearm;

Figure 5 illustrates a plan view of the connection on the side reverse from that shown in Fig. 4;

Figure 6 illustrates a sectional view on the line 6—6 of Fig. 5;

Figure 7 illustrates an enlarged detail view of one end of the strap;

Figure 8 illustrates an enlarged detail view of the strap near its inner end;

Figure 9 illustrates an enlarged detail view 70 of the seat for the outer end of the strap fitting;

Figure 10 illustrates a modified housing;

Figure 11 illustrates a sectional view of a further modification; and

Figure 12 is a section through the end of the winding drum shaft and its support.

In these drawings, 15 denotes the stock of a firearm having a stud 16 anchored to it near its outer end in any appropriate way, as by threading the said stud into the stock, and 17 denotes a loop or eye carried by the stud. The eye is provided with a transversely disposed slot 18 extending from one side to the centre and the said slot is intended as a clearance to permit the removal of a hook 19 therefrom, the said hook being carried by a plate 20 having a loop 21 that is slidable on the strap.

The plate has a transversely disposed groove 22 between the hook and the loop which forms a seat for the T-head 23 of a link 24 that is pivotally connected to the strap by a plate 25, which plate is doubled on itself and secured to the strap by fastenings 26, such as rivets or the like. As shown in Fig. 1 where the length of the strap is to be adjusted at its outer end, the member 20 having the hook is located in the looped portion 95 of the strap, as shown at 27, and the hook 100

thereof is applied to the eye 17 of the stud so that the strap is anchored to the stock. The strap is doubled on itself for the desired length and the T-head of the link is inserted in one of the slots 28 of the strap formed preferably longitudinally in the strap, (Fig. 7) and, by this means the adjustment of the outer end is attained.

As a means for storing the strap in the butt of the gun, a chamber is formed in the butt and a winding drum 29 for the strap is mounted therein. One form of the invention consists of cheek pieces 30 and 31 arranged in the side of the stock and they are associated with a housing in which the drum is rotatable. A shaft 32 is anchored to the cheek pieces. The shaft is preferably round between its ends and made angular in cross section between the side of the drum and the inner surfaces of the cheek pieces, the said angularly disposed portions of the shaft being fitted to supports of like configuration on the inner surfaces of the cheek pieces in order that the shaft will be prevented from rotating or from distortion (Fig. 12). The extremities of the shaft are round, although they may be otherwise shaped where they enter apertures 33 in the cheek pieces. After the housing has been applied to the stock, the usual end plate 34 will be secured in place to retain the parts assembled.

The drum 29 is rotatable on the shaft and is held under tension of a spring 35 which is so arranged as to turn the drum in a direction to wind the strap thereon, it being shown that the said spring is secured to the drum at 36 and to the shaft at 37. The strap is secured to the drum by a pin 38, or in any appropriate manner, in order that the strap may be wound on the drum or pulled therefrom when it is to be used. An escutcheon plate 39 is fitted to the outer surface of the stock, but it has a tubular portion 40 extending inwardly to the chamber in order that the strap may pass through the said tubular portion as it is pulled out by hand or drawn into the chamber through the action of the spring.

A certain part of the strap near its inner end may be provided with seats 41, such as holes, which are intended to receive pins 42 which will serve to hold the strap at different positions of adjustment, according to the length of strap for a certain user. It is shown in the drawings that the pins 42 are carried by a plate 43 slidably applied to the stock, and the said plate is operated by means externally of the stock, such as a thumbpiece 44, which is similar to the ordinary safety catch used in firearms.

It is shown in the drawings that the escutcheon plate is recessed so that it forms a seat for the fixtures which are on the outer end of the strap, to which reference has heretofore been made.

In a modified construction, the stock may be provided with a cavity in its end into which a housing 45 may be inserted, the said housing having a flange 46 at its end. In this form, the flange may be located in a recess formed in the end of the stock and it may be secured in place by fastenings applied to the apertures 47 in the flange. In this form of the invention, the escutcheon plate 48 and other features such as the strap and its fittings will be utilized and the drum will be mounted in the housing as it is mounted substantially as shown and heretofore described.

As a further modification of the invention, a housing 49 may be employed which constitutes a continuation of the gunstock 50. In this embodiment of the invention, the ordinary gunstock will be used, except that the outer end or butt thereof will be removed for an appropriate length, the length of which would be compensated by the size of the housing and, of course, the said housing will be shaped so that it will simulate the ordinary butt end of a gunstock. In the present illustration, the housing has an internal plate 51 at its inner end located a short distance from its inner end in order that the walls of the housing may extend beyond a portion of the outer end of the stock to produce a finished effect. In order to accomplish this, the stock will preferably be cut away to a depth equaling the thickness of the wall of the casing to produce a fit similar to that shown in Fig. 11.

The end of the stock may be provided with threaded bushings 52 anchored therein in appropriate way in order to engage screws 53 extending through the plate 51, it being understood that the said plate 51 is secured to the inner surface of the housing by appropriate fastening means such as welding or the like.

The housing 49 has at its outer end securing means for a butt plate 54 and, as here shown, lugs 55 are secured to the inner wall of the housing and screws 56 extending through the butt plate and the lugs serve to retain the parts assembled.

In this form of the invention, one wall of the housing is recessed as at 57 and apertured as shown at 58 to permit the strap, heretofore described, to be applied to or removed from the drum 59 which, it is understood, is to be mounted on the wall of the chamber in substantially the same manner as that heretofore described with respect to the mounting of the drum on the cheek pieces, as in that form of the invention shown in Fig. 1.

While I have referred to the sling strap as such, it is to be understood that any flexible device which has the function and purpose of such strap will be comprehended within the term adopted.

I claim:

1. In a device for adjusting sling straps of firearms, a stock, a stud attached thereto, said stud having an eye, a member having a hook adapted to engage the eye, said member having a loop, a strap on which the loop is slideable, a link having a T-head secured to the end of the strap, the said strap having apertures for the reception of the T-head of the link, whereby the end of the strap is secured to a portion of the strap between its ends, the said member having the loop engaging the looped portion of the strap for anchoring it to the stud.
- 15 2. In a device for adjusting sling straps of firearms, a member having a loop and a hook, a strap slideable through the loop, the said member also having a transversely disposed groove forming a seat, a link pivotally connected to the end of the strap and having a T-head adapted to lie in the groove of the member when assembled and to engage the strap between its ends for shortening the strap, and a member carried by the firearm 20 engaging the hook for holding the strap at its outer end.
3. In a firearm having a stock, a chamber at the butt end of the stock, a spring actuated drum mounted therein and having communication with the exterior of the stock, a strap movable through the said means of communication and wound on the drum, and a latch in the chamber of the stock engaging the strap at different positions and holding said 35 strap adjusted.
4. In a firearm, a stock having a chamber therein, an opening in the stock communicating with the chamber, the said chamber being adapted to receive a sling strap, and a latch in the chamber engaging and holding the sling strap at different positions of adjustment.
- 45 5. In a firearm, a housing applied to the butt end of a stock and forming an extension thereof, a winding member rotatably mounted therein, a strap extendable through the wall of the housing and applied to said winding device, and means for holding the strap at different positions of adjustment.
- 50 6. A fire arm having a stock with a chamber formed therein and an opening in its wall communicating with the said chamber, a drum in the said chamber, a strap wound on the drum and projecting through the opening, a latch comprising a plate slideable in the chamber and having a pin adapted to project across the opening in which the strap enters the chamber, said strap having apertures to receive the pin for adjustably retaining the strap at different positions.
- 55 7. In a fire arm, a housing, means for detachably securing the housing to the butt end of the stock of the fire arm to form an extension thereof, said housing having an open-

ing in its wall, a strap extendable through said opening, a winding member rotative in the housing on which the strap is wound, and a latch for holding the strap at different positions of adjustment.
